UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,203,061.

Specification of Letters Patent.

Patented Oct. 31, 1916.

Application filed December 31, 1915. Serial No. 69,601.

To all whom it may concern:

Be it known that I, GEORGE A. SEIB, citizen of the United States, and resident of Ilion, in the county of Herkimer and State 5 of New York, have invented certain new and useful Improvements in Type-Writing Machines, of which the following is a specification.

My present invention relates more particularly to stop devices for case-shifting type-writing machines and its main object is to minimize or reduce the noise incident to such case-shifting.

To the above and other ends my invention 15 consists in the features of construction, combinations of devices and arrangements of parts hereinafter described and particularly pointed out in the claims.

While my invention is applicable to various typewriting machines, the preferred construction herein illustrated is embodied in a stop mechanism of the general character disclosed in the patent to Merritt No. 874,784, granted December 24, 1907 wherein such 25 mechanism is employed to arrest and determine the movements of the shiftable type bar segment of the Monarch typewriting machine.

In the accompanying drawing, Figure 1 is 30 a fragmentary front elevation of the shiftable type bar segment of a typewriting machine, together with the supporting and guiding posts or uprights and associate parts, my improved stop devices being 35 mounted on said posts. Fig. 2 is a fragmentary rear elevation of some of the parts shown in Fig. 1, the segment, however, being represented in shifted position. Fig. 3 is a perspective view of one of the posts and 40 associate parts. Fig. 4 is a horizontal sectional view taken on a plane indicated by the dotted line $x-x$ in Fig. 1 and looking downward. Fig. 5 shows a modified stop device.

The main frame of the machine comprises 45 a base portion 1 from the sides of which rise stationary posts or uprights 2 that assist to support and guide the shiftable or movable type bar segment 3 that is controlled by key 50 operated devices including arms or links 4. In the present construction the segment when in its upper position as shown in Fig. 1 is adapted to write lower case characters and when shifted downward to its lower position 55 as in Fig. 2 is adapted to write upper case

characters. But the direction of shift from one case position to the other may be reversed, as it is in the present Monarch. Fixed to the posts 2 are grooved track-ways 5, oppositely grooved track-ways 6 being 60 fixed to the segment 3. Sets of anti-friction balls 7 are arranged in the associate track-ways and furnish bearings for the shiftable segment 3, each set of balls being provided with a separator 8 interposed between the 65 track-ways 5 and 6.

The up and down shifting movements of the segment 3 along the fixed guiding and supporting devices 2, 5 are limited by stop devices comprising at each side of the segment 70 an upper lug or stop 9 and a lower lug or stop 10 both fixed to and projecting rearward from the back of the segment. Each pair of stops 9 and 10 coöperate with stop devices of novel construction adjustably secured in pairs to the rear faces of the posts 2. The novel stop devices 11 and 12 comprised in each pair are essentially alike. Each of said stop devices is in the form of a split plate or arm horizontally arranged and 75 slidably fitted into a groove in the back of the post or stationary part 2. Headed screws 13 pass through slots 14 in the body of the stops 11 and 12 and are threaded into the posts, said screws adjustably securing the stops to the posts and the slots 14 permitting the stops to be adjusted horizontally inward and outward to vary the point of arrest of the segment. The inner end portion 80 of each of the stop devices or plates 11 and 12 is formed with a slot or kerf 15 preferably terminating at 16. The slots 15 divide the stopping end of each of the devices 11 and 12 into tongues 17 and 18. The stopping ends of the stops 9 and 10 are preferably 85 oppositely beveled and the coöperating end portions of the stops 11 and 12 are correspondingly beveled or inclined in opposite directions as indicated at 19. The tongues 95 17 with which the stops 9 and 10 directly engage have slightly divergent sides, said tongues being somewhat thinner or narrower near their free ends than farther back toward their roots. In other words, the tongues 17 are slightly wedge-shaped. These 100 tongues or stops proper are so constructed that while they coöperate with the stops 9 and 10 positively to arrest the segment 3 and limit its movements in both directions, they, nevertheless, are sufficiently yielding to pre-

110

vent a sudden, violent and noisy arrest of the segment. Consequently my novel stop devices minimize or reduce to a considerable extent both the noise and the jarring incident to such arrest.

5 While the slot 15 is shown in Figs. 1 to 4 as made nearer one edge of the stop device than the other, said slot may, however, be made centrally of the body or shank of the 10 plate 11 or 12, as shown at 15^a in Fig. 5.

The stops of my invention have been embodied in full-sized operative typewriting machines, and their use has demonstrated in practical operation that the shifting of the 15 segment from one case position to the other is made with vastly less noise or sound than with the use of the solid stops heretofore employed.

It will be observed that by my present invention I provide novel stop devices for limiting the movement between the two relatively movable parts, viz., the type bar segment and the guide post or pair of guide posts, the relative movement between the 25 parts being caused by shifting the segment; that said stop devices comprise a split stop which, in the present instance, is a plate-like part having a kerf or cut that forms two tongues, one of the tongues being slightly 30 wedge-shaped and coöperating with a stop lug or projection, 9 or 10; and that said stop devices also comprise two tongues or members arranged one under the other close together but out of contact.

35 Various changes in detail construction and arrangement may be made without departing from the spirit of my invention.

What I claim as new and desire to secure by Letters Patent, is:—

40 1. In a typewriting machine, the combination of two relatively movable parts, and stop devices for limiting relative movement between said parts, said stop devices comprising a pair of closely arranged substantially parallel tongues, one of said tongues 45 only being adapted for contact with a coacting stop device.

50 2. In a typewriting machine, the combination of two relatively movable parts, and stop devices for limiting relative movement between said parts, said stop devices comprising a lug and also two tongues, the lug being adapted to contact with one only of 55 said tongues.

55 3. In a typewriting machine, the combination of two relatively movable parts, and stop devices for limiting relative movement between said parts, said stop de-

vices comprising a stop or lug and a stop plate split or cut to provide two tongues, 60 one of said tongues being slightly wedge-shaped and coöperating directly with said lug to limit the movement of the parts in one direction.

4. In a typewriting machine, the combination of a shiftable type bar segment, a supporting post, a stop lug on one part, and a co-operating split stop on the other part, said split stop being adjustable to vary the point of arrest of said segment, said split stop consisting of a pair of closely arranged substantially parallel tongues, one only of said tongues being adapted for contact with said stop lug.

5. In a typewriting machine, the combination with a shiftable segment, of means for arresting the same comprising an integral device consisting of two tongues or members arranged close together but out of contact.

6. In a typewriting machine, the combination with a shiftable segment, of means for arresting the same comprising a one-piece device consisting of two tongues one under the other but slightly spaced apart.

7. In a typewriting machine, the combination with a shiftable segment having contact devices, of segment stops comprising slide bars formed each with a pair of spaced tongues, the said slide bars being so arranged that only one tongue of each pair of tongues 90 is struck by one of the contact devices on the shiftable segment.

8. In a typewriting machine, the combination of an up and down shiftable segment provided with stopping devices, and a pair 95 of split stops fixedly arranged transversely of said stopping devices on said segment to coöperate with said stopping devices.

9. In a typewriting machine, the combination of two relatively movable parts, two 100 split stops on one of said parts, and two co-acting stops on the other of said parts, one of said split stops coöperating with one of said co-acting stops to limit the movable part in one direction and the other of said 105 split stops coöperating with the other co-acting stop to limit the movement of said movable part in the opposite direction.

Signed at Ilion, in the county of Herkimer and State of New York, this 29th day 110 of December, A. D. 1915.

GEORGE A. SEIB.
